CLAIM

The ornamental design for a woman nightdress, as shown and described.

DESCRIPTION

FIG. 1 is a front elevational view of a woman nightdress showing my new design;

FIG. 2 is a rear elevational view thereof;

FIG. 3 is a left elevational view thereof; and,

FIG. 4 is a right elevational view thereof.

The broken lines depict environment that forms no part of the claimed design for the woman nightdress.
